UNITED STATES PATENT OFFICE

HERBERT F. HUNTER AND LELAND S. HANNOLD, OF SWEDESBORO, NEW JERSEY.

RADIOWAVE RECEIVING DEVICE.

Application filed May 8, 1924. Serial No. 711,842.

To all whom it may concern:

Be it known that we, HERBERT F. HUNTER and LELAND S. HANNOLD, citizens of the United States, residing at Swedesboro, in the county of Gloucester and State of New Jersey, have invented certain new and useful Improvements in Radiowave Receiving Devices, of which the following is a specification.

10 This invention relates to a radio wave receiving device, and particularly to a construction adapted for use with radio receiving sets of the audion bulb type, and is adapted for increasing the receptive capacity of these sets, without the use of an antenna.

20 An object of the invention resides in providing a device of the character above mentioned, which is adapted for use to increase the volume of a received signal, increase the activity in tuning, and eliminate objectionable noises and static interference.

25 Another object of the invention resides in providing a wave receiving device, for use in connection with the audion bulb type of radio receiving circuit, wherein a plurality of inductance coils are mounted in axial relation, the coils at one end being connected in parallel with a variable condenser and having an electrical connection with a metallic sleeve, positioned over the central portion of the coil at the opposite end, in order that an inductive relation will be set up between coils when positioned over the central portion of a radio receiving set, for receiving radio wave signals and inductively transmitting such signals to the receiving circuits of the set, one side of the condenser and first mentioned inductance coil being provided with a ground connection for increasing the receptive qualities of the device, without the use of antennae, and for absorbing and eliminating undesirable noises and static interference, while at the same time increasing the volume and selectivity of signal reception.

30 The invention also comprehends other objects and improvements in the details of construction and arrangement of the parts, which are more particularly pointed out in the following description and claims directed to a preferred form of the invention, it being understood, however, that various changes in the construction, may be made, without departing from the spirit and scope 35 of the invention, as described and claimed.

In the drawings, forming a part of this application:

Figure 1 is a view of the invention, showing the casing in section and the remaining portions in elevation.

Figure 2 is a sectional view, taken on the line 2—2 of Figure 1.

Figure 3 is a transverse sectional view, taken on the line 3—3 of Figure 1.

Figure 4 is a longitudinal sectional view, 65 through one end portion of the device.

Figure 5 is a longitudinal sectional view, similar to Figure 4, taken through the other end portion of the device, and Fig. 6 is a diagrammatical showing of one manner of 70 using the device.

The invention includes a casing 1, preferably of elongated tubular form, closed at its ends by suitable end plates indicated at 2. A variable plate condenser 3 is mounted 75 on one end plate 4, within the casing 1, and which end may be termed the forward end for the purpose of distinction, the position of the plates being varied by the usual adjusting dial 4, mounted on the shaft of the 80 condenser, which is extended through the forward end plate 2, in a manner clearly shown in Figure 1. A pair of binding posts 5 and 6 respectively, are mounted in the casing 1, at diametrically opposite 85 points, adjacent the forward end thereof, and are each electrically connected with the opposite terminals of the condenser, the binding post 5 being connected with the rotor or movable plate, while the binding post 90 6 is connected with the stationary plate. A substantially elongated tube 7, is mounted in the casing 1, in concentric relation therein, and is preferably constructed of suitable insulating material, for receiving inductance coils 8 and 9 respectively, the coil 8 being provided with a substantially large number of windings, while the coil 9 has relatively few windings. A tube 10, of slightly smaller diameter than the tube 7, is mounted between the end of the tube 7 and the variable condenser 3, in concentric relation with the tubular casing 1, one end of the tube 10 projecting into the tube 7, in a manner as clearly illustrated in the drawing. This tube 10 is provided with a coil winding, indicated at 11, extending substantially the entire length thereof, and having a relatively large number of turns, the end portions of the coil being electrically connected with the

110

opposite terminal of the variable condenser. This is effected through the wire connection 12, from the end of the coil adjacent said condenser with the stationary plates thereof, while the wire connection 13 extends from the movable plates of the condenser through the central portion of the coil to the opposite end of the winding, as indicated at 14. A sleeve 15 preferably of copper, is positioned, on the coil 8, intermediate the ends thereof, and extends over substantially one-third of the windings of the coil, and is electrically connected by a wire 16, with the coil 11, at the point 14, at one end thereof. 15 A split sleeve member 17 preferably formed of copper, is positioned over one end portion of the coil 8, and the adjacent end portion of the coil 9, and is provided with an electrical connection indicated at 18, for the binding post 19, mounted on the casing 1, in the central portion thereof. The end of the coil 8, at the rear end of the casing 1, is connected with the binding post 20 at the rear end of the casing, in order that the coil 8 25 may be connected in circuit to an antenna as will be explained.

The three coil windings 8, 9, and 11, in being arranged in axial relation, provide for relative inductance between the coils, while the copper sleeves and wiring connections in the casing, provides for the flow of energy through the coils, and the sleeve, particularly the signal energy which it is desired to receive. The coil 9 is not electrically connected with any other element, and is interposed between the coils 8 and 11 for preventing stray forces from affecting the inductive action from between the coils and preventing interference with the inductive cooperation of said coil.

40 The use of the device is indicated in Figure 6, wherein 21 indicates an audion bulb type of receiving set, having aerial and ground contacts at 22, and in which the tubes of the several stages of amplification are usually arranged, in alignment lengthwise of the set. The device may be placed directly on top of the set 21 as indicated by dash lines, in Figure 6, at 23, in which case 45 the terminal 6, is provided with a wire connection to a suitable ground, and by properly tuning the condenser 3, wave signals will be received in the several inductances, and inductively transmitted to the circuit 50 of the receiving circuit 21 for properly receiving and amplification.

55 In the use of the device in this manner, it has been found by experiments, that substantially weak signals can be received and amplified without local or static interference, and at the same time materially reducing the use of an aerial. The received signals may be louder and clearer in the reproducing device of the receiving set with 60 the use of the present invention than when

the same is connected with an aerial and ground, in the usual and well known manner.

If desired, a vario coupler 25 may be used in connection with the set 21, by having the 70 rotor windings connected to the aerial and ground terminals by suitable wires 26, while the stator of the vario coupler is connected by wires 27 to the binding posts 5 and 19 respectively, of the wave receiving device, in the casing 1, while the binding post 6 is connected with the ground by a wire 28, and binding post 20 is connected with an antenna 29 as indicated. In this use of the device, the operation of the vario coupler 25 75 and the condenser 3 is effected, for tuning the detector circuit, in connection with the tuning devices in the set, in receiving a signal, while undesirable interferences are absorbed in the device, by transmission in the 80 several inductance coils and carried through to the ground, and the signal impressed in the proper circuit for transmission to the receiving set 21.

In the use of this device, it will be seen 90 that an aerial is not absolutely necessary, and that the reception of signals may be effected by the inductive cooperation of the invention with the receiving set, or by direct transmission thereto, in both cases, the 95 result being increased volume, and consequently range of reception, together with exceedingly fine selectivity.

It will be apparent from the foregoing 100 description, that a simple and convenient form of device has been provided, for use in conjunction with radio sets for effecting an increased selectivity of the set, increased receptive range, and increased volume in the received signals, and at the same time eliminating the use of an antenna.

What is claimed is:

1. A device of the class described, comprising a casing, a plurality of inductance coils mounted in axial relation therein, a variable condenser mounted in one end of the casing, in line with said coils and electrically connected in parallel with the adjacent coil, binding posts on the casing, a pair of connections extending from opposite terminals of the condenser and connected coil to a pair of binding posts, and a circuit connection between the first mentioned coil, and the coil at the opposite end, and a metallic sleeve mounted on the coil at the opposite end of said casing, whereby said coils may be arranged in inductive relation with a radio receiving set for having circuit connections therewith to increase the signal receiving qualities of said set.

2. A device of the class described including a tubular casing, a variable condenser mounted at one end to said casing, and a plurality of inductance coils mounted in axial relation in said casing, adjacent said con-

denser, the coil adjacent said condenser having its ends connected to the terminals of the condenser, circuit connections being provided for connecting one terminal of the condenser and coil with the ground, and a connection being provided with the other terminals of the condenser and coil, and a metallic sleeve mounted on the inductance coil, at the opposite end of the casing, an intermediate coil, and the end coil having the metallic sleeve thereover, having their ends terminating in adjacent relation, a metallic sleeve being positioned over said adjacent end for permitting a transmission of energy between said coils, the first mentioned coil having a second binding post connection on the casing, and the last mentioned sleeve having a binding post connection on said casing adapted for electrical connection with the radio receiving set, for cooperation therewith, to increase the volume of signal reception.

3. A device of the character described including a tubular casing having a condenser mounted in the forward end thereof, having electrical connection with a pair of binding posts mounted on the casing, a plurality of inductance coils mounted in axial relation in said tube, the coil adjacent said condenser having the terminals connected to the said condenser, the coil at the rear end of the casing having a relatively large number of windings and connected at the rear end to a binding post carried by the casing, a metallic sleeve mounted in the central portion of the coil, at the rear end of the casing, having electrical connections with one end of said condenser, and first mentioned coil, the coil winding intermediate said first mentioned coils and mounted in the central portion of the casing terminating adjacent the ends of said coils, a split metallic sleeve member mounted over one end of the central coil and the adjacent end of the coil at the rear of the casing, and electrically connected with the binding post on said casing, whereby said coils cooperate with the metal sleeves and condenser, for receiving and inducing or transmitting radio signals to the receiving set and increase the volume, range, and selectivity of said set.

4. A device of the class described, comprising a plurality of inductance coils mounted in axially aligned inductive relation, and a variable condenser connected in parallel with one of the inductance coils and having an inductive connection with another of said inductance coils spaced from the first mentioned inductance coil, one terminal of

the condenser and connected inductance coil and one terminal of the second mentioned inductance coil forming terminals of an inductively coupled primary circuit, the other terminal of the condenser and connected coil and an inductive connection with the second mentioned inductance coil and an adjacent inductance coil forming an inductively coupled secondary circuit inductively arranged with the primary circuit.

5. A device of the class described comprising a plurality of inductance coils mounted in axially aligned inductive relation, a variable condenser connected in parallel with the coil at one end of the plurality of coils, a member arranged in inductive relation with the coil at the opposite end of the plurality of inductance coils, a wire connection with one terminal of the condenser and the member, and a member inductively arranged with the last mentioned inductance coil and an adjacent coil, one terminal of the condenser and one end of the second mentioned inductance coil forming terminals for connection in a primary circuit, a terminal with the second mentioned member and the other condenser terminal for connection to a secondary circuit.

6. A device of the class described comprising a plurality of axially aligned independent inductance coils arranged in inductive relation without electrical connection, a variable condenser electrically connected in parallel with one of said coils, all of said coils and the condenser adapted to be included in an inductively coupled primary circuit, and a secondary circuit having one terminal electrically connected to the coil, and connective condenser, and the other terminal capacitatively connected to other of said inductive coils.

7. A device of the class described including a primary circuit including a plurality of axially aligned independent inductance coils, without electrical connection and inductively associated, a variable capacity having the terminals electrically connected to one of said coils, a capacity connection with one terminal of the last mentioned coil and capacity, and another inductance coil, and a secondary circuit having an electrical connection with the first mentioned capacity coil, and a capacity connection with other of said coils.

In testimony whereof we affix our signatures.

HERBERT F. HUNTER.
LELAND S. HANNOLD.
